INVENTOR,
Frank S. Ingoldsby.

UNITED STATES PATENT OFFICE.

FRANK S. INGOLDSBY, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

DUMP-CAR.

1,026,397.

Specification of Letters Patent.

Patented May 14, 1912.

Application filed July 2, 1907. Serial No. 381,902.

To all whom it may concern:

Be it known that I, FRANK S. INGOLDSBY, a citizen of the United States, residing at St. Louis, State of Missouri, have invented a certain new and useful Improvement in Dump-Cars, of which the following is a full, clear, and exact description, reference being had to the accompanying drawings.

This invention relates to dumping cars having load supporting doors which drop to discharge the load across them.

The object of the invention is to arrange such a car with supporting mechanism for the door which shall be very simple and effective in construction and shall allow a maximum discharging surface for the door, whereby it may carry the material to the most advantageous point.

The invention is particularly well adapted for cars of the Ingoldsby type wherein there is a central longitudinal member to the opposite edges of which are hinged dumping doors which extend outwardly to the car sides when closed, these doors being supported at the car sides or released to swing downwardly at their outer edges to discharge the load across them.

In the Ingoldsby cars, hooks have been provided on the sides of the car engaging with floor beams on the underside of the doors to support the doors. These floor beams have heretofore extended beyond the outer edges of the doors, and have been provided with hooks engaging the outer sides of the supporting hooks to prevent outward bulging of the car sides.

In the present invention I extended the surface of the door beneath the supporting hooks to the end of the floor beams and provide slots through the door sufficient to allow the passage of the supporting hooks. I thus at once avail myself of a wider door than is possible with the projecting floor beams and at the same time I prevent outward bulging of the car side by reason of the outer edge of the slots in the doors engaging the supporting hooks.

By this invention, I have provided a simpler and, for some purposes, a more efficient

structure than the former construction referred to.

The invention is herein after more fully explained in connection with the accompanying drawings.

In the drawings Figure 1 is a vertical cross section through a car embodying my invention. Fig. 2 is a portion of a side elevation of such car adjacent to one of the supporting hooks. Fig. 3 is a plan of a portion of one of the doors removed. Fig. 4 is a vertical cross section through a portion of a wooden car adjacent to the lower edge of the side and the outer edge of the door.

Referring first to Figs. 1, 2 and 3, 10 represents the plate of a girder side, and 11 the lower chord of such side. 12 indicates the central longitudinal ridge member to which are hinged dumping doors 13, these doors being provided with floor beams 15 which are in the form of angle bars. The inner ends of these angle bars may be bent around onto themselves to form hinge eyes as shown at 16. The plate or surface 13 of the door extends beneath the side plate 10 of the car and beneath the lower chord. This surface is provided with slots 20 adjacent to the floor beams, and extending parallel with the longitudinal edge of the car, these slots being so placed that when the door is closed they come outside of the side plate of the girder and directly beneath supporting hooks 21 which are pivoted to the sides of the car.

As shown in Figs. 1 and 2, the supporting hooks are mounted on blocks 23 carried by the car sides, and the hooks extend through slots in a horizontal flange of the lower chord, and adapted to pass through the slots 20 in the doors and engage the under side of the floor beams. The lower portion of the hooks are curved in an arc about the hinge of the door as a center, so that the supporting hooks may occupy the slots comparatively closely and still clear the same. It will be seen that when in locked position the supporting hooks by reason of their beveled ends draw the door snugly into place, while the outer wall of the slots prevent any out-

ward bulging of the car side. When the door is dropped to the proper dumping angle it may still extend a considerable distance beyond the rail and thus carry the dis- 5 charging load to the point desired. By having the surface of the door engage the side plate of the car instead of the lower chord itself, a tighter joint may be effected; for in case any material sticks to the door, the com- 10 paratively thin plate will cut through such material.

Fig. 4 illustrates the invention adapted to a wooden car. Here the surface 13 of the door may be of wood and the lower chord 11 of the car side 10 may also be of wood. 15 represents a plate secured along the inner face of the lower chord and depending from it, the door abutting the lower edge of this plate to make the tight joint referred to. 20 The levers 21 are carried by blocks 23 supported by the car side, and the doors have their surface slotted to receive the levers as already described.

It will be seen from the above description 25 that my improvement is equally adaptable for steel and wooden cars; that it simplifies the construction over my prior arrangement of double locking hooks, and provides a more extended door surface for the material 30 to run on during discharge, thus carrying it farther out from the rail.

I claim:

1. The combination, in a dump car, of a load supporting door having a surface with 35 an opening through it and a floor beam on its under side adjacent to such opening and a supporting member adapted to extend through the opening and engage the floor beam to hold the door, said means being 40 movable to release the floor beam and door.

2. In a dump car, the combination with a car side, of a hinged door having its free edge coöoperating with such side and having an opening near such side, and a support- 45 ing hook carried by the car side on its outer side and adapted to extend through such opening.

3. The combination, in a dump car, of a car side, a hinged door having a load sup- 50 porting surface with an opening through it and a floor beam on its under side adjacent to such opening, and a supporting member carried by the car side and adapted to extend through the opening and engage the 55 floor beam or be moved in the opening to free the floor beam.

4. In a dump car, the combination of a car side having a plate with a comparatively narrow lower edge, a dumping door adapted 60 to engage such edge, and means carried outside of such edge for supporting the door.

5. In a dump car, the combination with a car side having a lower chord and a nar-

row plate extending lower than such chord, a dumping door having a load supporting 65 surface adapted to extend beneath and en- gage the lower edge of such plate, and sup- porting hooks carried by the car side and adapted to extend through openings in the door surface beyond such narrow plate. 70

6. In a dump car, the combination of a longitudinal center member, dumping doors hinged thereto and extending outward be- 75 yond the car side, openings through the doors near the outer edges thereof and hooks on the outer sides of the car sides adapted to pass through such openings and engage the under side of the door.

7. In a dump car, the combination of a longitudinal center member, dumping doors 80 hinged thereto and extending outward to the car side, floor beams for said doors, open- 85 ings through the doors adjacent to the floor beams near the outer edges of the doors, and hooks on the outer sides of the car sides 90 adapted to pass through such openings and engage the under side of the floor beams.

8. The combination of a dumping door 90 having a floor beam in the form of an angle bar and a supporting hook arranged to pass through an opening in the surface of the door and engage beneath the depending flange of the angle.

9. In a dump car, the combination of a dumping door hinged at one edge and hav- 95 ing near its other edge a longitudinal slot parallel therewith adapted to stand outside of the side wall, and a supporting member adapted to extend through said slot, said member and slot coöperating to prevent the 100 outward bulging of the car side.

10. The combination of a dumping door having its longitudinal edge adapted to co- 105 operate with the car side, an opening through said door near said longitudinal edge adapted to stand outside of the side wall, and a member carried by the car side and adapted to extend through such opening to support the door and prevent the 110 outward bulging of the side.

11. In a dump car, the combination of a load supporting dumping door hinged near one edge and having a longitudinal slot near 115 its outer edge and beyond that part of the door engaged by the side of the car.

12. In a dump car, the combination of a hinged dumping door having a slot through it adjacent the edge opposite the hinge, and non-flexible means for supporting the door and adapted to extend through such slot 120 and engage the under side of the door.

13. In a dump car, the combination of a hinged door having an opening through it adjacent the edge opposite the hinge, and a hook adapted to extend through such open- 125 ing and engage the under side of the door.

14. In a dump car, the combination of a hinged dumping door having an opening through it near its free edge opposite the hinge, a supporting member adapted to extend through such opening and engage the under side of the door, said member being adapted to disengage the door to release it, and a pivotal support for the said member

holding it whether it engages or releases the door.

In testimony whereof, I hereunto affix my signature in the presence of two witnesses.

FRANK S. INGOLDSBY.
